Primary Examiner—Brian N. Vinson*Assistant Examiner*—Robin V. Taylor*Attorney, Agent, or Firm*—Senniger, Powers, Leavitt & Roedel[57] **CLAIM**

The ornamental design for a bag support insert with funnel top, as shown and described.

DESCRIPTION

FIG. 1 is a front and right side perspective view of a bag support insert with funnel top showing my new design. The broken line showing of a lawn refuse bag is for illustrative purposes only and forms no part of the claimed design;

FIG. 2 is a front view thereof, shown in its flat, unfolded configuration;

FIG. 3 is a front elevational view thereof;

FIG. 4 is a back elevational view thereof;

FIG. 5 is a right side elevational view thereof;

FIG. 6 is a left side elevational view thereof;

FIG. 7 is a top plan view thereof; and,

FIG. 8 is a bottom plan view thereof.
